(57) **CLAIM**

The ornamental design for camera equipment bracket as shown and described.

DESCRIPTION

FIG. 1 is a front elevational view thereof;
FIG. 2 is a rear elevational view thereof;
FIG. 3 is a left side view thereof;
FIG. 4 is a right side view thereof;
FIG. 5 is a detailed view of the portion labeled 5 in FIG. 4;
FIG. 6 is a top plan view thereof;
FIG. 7 is a bottom plan view thereof;
FIG. 8 is a rear perspective view thereof;
FIG. 9 is a front perspective view thereof;
FIG. 10 is a perspective view in a state of use thereof;
FIG. 11 is a perspective view in a closed state thereof; and,
FIG. 12 is another perspective view in another state of use.
The broken lines depict portions of the camera equipment bracket and forms no part of the claimed design. The dot-dash broken lines seen only in FIG. 4 and FIG. 5 are for the purpose of disclosing an enlarged detailed view and forms no part of the claimed design.

1 Claim, 11 Drawing Sheets
